ATTORNEY.

UNITED STATES PATENT OFFICE.

EUGENE L. HOWE, OF CLEVELAND, OHIO, ASSIGNOR TO THE EBERHARD MANUFACTURING COMPANY, OF SAME PLACE.

DESIGN FOR A HARNESS-TERRET.

SPECIFICATION forming part of Design No. 19,151, dated June 11, 1889.

Application filed May 10, 1889. Serial No. 310,321. Term of patent 7 years.

To all whom it may concern:

Be it known that I, EUGENE L. HOWE, a citizen of the United States, and residing at Cleveland, in the county of Cuyahoga and State of Ohio, have invented and produced a new and original Design for a Harness-Terret, of which the following is a specification, reference being had to the accompanying drawings, forming part thereof.

10 Figures 1 and 2 are respectively elevation and plan of a terret embodying my design.

The band or ring A of the terret on the upper side thereof is divided obliquely with the plane of such band or ring, the intervening space being sufficient to admit the rein edge-wise. The overlapping points of the band or ring adjacent such opening deflect outward,

as shown at *a a*, and terminate in small balls, approximately spheres, *a'*.

What I claim is—

20 The design for terret herein shown and described, the same comprising a band or ring divided obliquely, the overlapping ends thereof deflecting outward and terminating in enlarged ends, approximately spheres, substantially as set forth.

25 In testimony whereof I sign this specification, in the presence of two witnesses, this 7th day of December, 1888.

EUGENE L. HOWE.

Witnesses:

M. O. SENENY,
W. H. BERSCH.
